CARD FILE

Donald Lee McFarland, Santa Barbara, Calif., assignor to
Eldon Industries, Inc., Hawthorne, Calif.

Filed Aug. 23, 1971, Ser. No. 174,298

Term of patent 14 years

Int. Cl. D19—99

U.S. Cl. D74—2 A

FIG. 1 is a perspective view of a card file embodying a new design of my invention;

FIG. 2 is a side-elevational view of the card file shown in FIG. 1, this view illustrating the side of the card file not visible in FIG. 1;

FIG. 3 is a top plan view of the card file shown in FIG. 1;

FIG. 4 is a front elevational view of the card file shown in FIG. 1;

FIG. 5 is a rear elevational view of the card file shown in FIG. 1;

FIG. 6 is a bottom plan view of the card file shown in FIG. 1; and

FIG. 7 is a perspective view of the card file shown in FIG. 1 as it appears with the front plate of the card file in a lowered position.

I claim:

The ornamental design for a card file, substantially as shown.
